US0D1059331S

(12) **United States Design Patent** (10) **Patent No.:** **US D1,059,331 S**
(45) **Date of Patent:** **** Jan. 28, 2025**

(54) **REMOTE CONTROL**

(71) Applicant: **Roku, Inc.**, San Jose, CA (US)

(72) Inventors: **Gregory Michael Hogan**, Dublin, CA (US); **Paul Nangeroni**, San Carlos, CA (US); **Anthony John Wood**, Palo Alto, CA (US); **Fred Bould**, Menlo Park, CA (US); **Jeremy Wolf**, San Francisco, CA (US)

(73) Assignee: **ROKU, INC.**, San Jose, CA (US)

(**) Term: **15 Years**

(21) Appl. No.: **29/951,420**

(22) Filed: **Jul. 9, 2024**

Related U.S. Application Data

(63) Continuation of application No. 29/892,498, filed on May 18, 2023, now Pat. No. Des. 1,035,623, which is a continuation of application No. 29/782,400, filed on May 6, 2021, now Pat. No. Des. 991,223.

(57) **CLAIM**

The ornamental design for a remote control as shown and described.

DESCRIPTION

FIG. 1 is a top perspective view of a remote control showing the claimed design;

FIG. 2 is a bottom rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the figures show portions of the remote control that form no part of the claimed design.

1 Claim, 6 Drawing Sheets
